UNITED STATES PATENT OFFICE.

JAMES G. MARCUM, OF JOPLIN, MISSOURI, ASSIGNOR OF ONE-HALF TO FRANK CHILDRESS, OF JOPLIN, MISSOURI.

SAFETY DEVICE FOR MINE SHAFTS.

Application filed October 3, 1924. Serial No. 741,519.

This invention relates to safety devices for mine shafts.

It is well known that miners are often exposed to grave danger in mines having open shafts, as it often happens that lumps of ore, rock or other solid substances fall down into the mines thru the shafts. As hoists of various kinds are employed in mines, these must pass thru the shafts which necessitates 10 that the shafts shall be so constructed that they may be opened wide enough to permit the cage or bucket to pass up and down.

It is the object of this invention to provide the shafts with doors that can be closed 15 so as to guard against articles of any description falling from the surface into the mine and which at the same time will open to let a cage or bucket pass upwardly and automatically close after the cage has 20 passed. I also provide means for opening the doors so as to permit the cage to move downwardly.

My invention can be most readily understood and most clearly described when reference is had to the accompanying drawing, 25 in which the preferred embodiment thereof is shown and in which

Fig. 1 is a vertical section of a mine shaft, taken on line 1—1, Fig. 2, showing the same 30 equipped with safety doors constructed in accordance with my invention, and

Fig. 2 is a section of the same shaft taken at right angles to that in Fig. 1 and along line 2—2, Fig. 1.

In the drawing, I have illustrated my 35 invention in its preferred form. Numeral 10 designates a vertical shaft thru which a cage or skip travels. I have not shown the hoist as that is old and well known and forms no 40 part of my invention, but have limited the drawing to the safety device and the means by which it is operated. The shaft is enlarged at a point located some distance beneath the surface of the ground. A rectangular frame comprising end pieces 11 and side pieces 12 is placed on the ledge 13 which 45 forms the bottom of the enlargement. Pivotally mounted at 14 and 15 are doors 16 and 17. These doors may be made of wood or 50 steel, but have been shown as constructed from a steel frame and covered with a steel plate. As will be noticed from Fig. 1, the doors are so wide that when they are in closed position, they form a gable roof.

When the doors are in open position, they 55 occupy the position indicated by dotted lines in Fig. 1. It is necessary to a successful operation of my safety device that the doors shall open and close simultaneously. For the purpose of opening the doors, I provide 60 a cable 18 whose lower end is connected to door 17 at 19. This cable passes thru the pulleys 20 and 21 in the manner shown. A second cable 22 has its end connected at 23 and 24 respectively to doors 16 and 17 and 65 passes around a pulley 25. Let us now assume that a force of sufficient value is applied to the cable 18 to move the same upwardly. This will move the doors from the full line to the dotted line positions in Fig. 70 1 or to open position. Since the doors are quite massive and are mounted on pivots, 14 and 15, which oppose very little resistance to rotation, and since they are never opened to a vertical position, they always tend to 75 close. If the tension in the cable 18 is released, the doors will immediately start closing, but the door 16 can close no faster than the door 17 on account of the cable 22. In order that the door 17 shall stop at the 80 proper place and that it shall not pass beyond the point shown in full lines in Fig. 1, I have secured the same by means of a short length of cable 26 with one of my uprights 27. It is therefore evident that the doors 85 will always come together in the position shown in Fig. 1.

The cable 18 extends to the top of the ground and may be fastened to a hoisting drum or other means by which it may be 90 manipulated for the purpose of opening and closing the doors.

If the shaft is employed for a hoist, the doors are opened to permit the cage or skip to descend after which they may be closed 95 and remain closed until the cage ascends, when the doors are opened to let it pass and are again closed as soon as the cage has passed thru. In this way the workmen in the mine are protected against injury from 100 falling objects of all kinds.

It is, of course, evident that as many sets of doors may be provided as may be deemed necessary, as this requires only a duplication of the doors described. The location 105 of the doors along the shaft is also a matter of choice. Some may desire to have them quite near the top while others may be of

the opinion that some other location is better. I therefore do not desire to be limited to any particular location.

I also wish to call attention to the fact
5 that the operating cables may be extended to any and as many place or places as it may be found desirable to have the hoist operated from.

Having now described my invention, what
10 I claim as new is:

A safety device for mine shafts comprising
a vertical shaft having an enlargement,
a rectangular frame located in said enlargement,
15 said frame lying in a substantially horizontal plane, the opening in said frame corresponding with the opening in the shaft,

a door hinged to each of the opposite side members of said frame, each door being wider than one-half the distance between the axes about which the doors swing, means for 20 preventing the doors from overlapping, means comprising a cable secured to one of said doors and passing about a pulley located above and to the rear of the door whereby when a pull is exerted on the cable 25 the door will be moved about its pivot to open position and means connecting the doors which causes them to open and close in unison when the cable is moved in one direction or the other.

In testimony whereof I affix my signature.

JAMES G. MARCUM.
